UNITED STATES PATENT OFFICE.

HARRY E. GIFFORD, OF MEDFORD, MASSACHUSETTS.

DOORCHECK.

Application filed October 8, 1924. Serial No. 742,475.

To all whom it may concern:

Be it known that I, HARRY E. GIFFORD, a citizen of the United States, residing at Medford, in the county of Middlesex and 5 State of Massachusetts, have invented new and useful Improvements in Doorchecks, of which the following is a specification.

My invention relates to improvements in door checks of the type used in keeping 10 screen doors closed, thereby eliminating the necessity of a latch.

The object of my invention is to supply 15 a door check which permits the door to close easily yet requiring considerable force to open the door; to give a simple yet strong construction; to supply a striking-plate for the door to receive the wear of the latch-bolt of the door check.

I am aware that there are door checks 20 having one spring of strong resistance which must be overcome in both opening and closing the door. Such door checks prevent the door from closing in many instances unless much force is exerted in the closing, or 25 the door is closed with a long strong swing. If such force is not exerted, the door remains partially open resting against the door check, permitting the entrance of flies and other insects. My door check eliminates this 30 objection, also extends the life of the door check by distributing the wear from one spring to several.

I attain my object by the construction 35 illustrated in the accompanying drawings, in which—

Figure 1, is a side view of my door check; the latch-bolt and its spring and manipulator being shown in dotted lines.

Figure 2, is a top view of my door check 40 showing springs on either side of the casing.

Figure 3, is a view of my door check in the position it assumes when the door is 45 opened, the latch-bolt engaging the striking-plate on the door.

Figure 4, is a plan view of the striking-plate.

Figure 5, is a side view of a modification 50 of my device with the casing spring located within the casing and shown in dotted line.

Figure 6, is a top view of Figure 5 with

the top of the casing, Figure 5, broken away at line *x*—*x*.

Figure 7, is an end view of the casing showing its formation. 55

Figure 8, illustrates a further modification of my device.

Similar numerals refer to similar parts throughout the several views.

1 is the base-plate of the door check having two lugs 2—2 to which is pivoted the casing 5; base-plate 1 has ears 3—3 through which are passed screw-eyes 4—4 for securing the door check to the door casing, and to receive the ends of springs 10—10; 6—6 are rivets by means of which the base-plate is pivoted to the casing 5; 7—7 are ears extending at right angle from the upper portion of casing 5, and are perforated to receive ends 11—11 of springs 10—10; 8 is the latch-bolt manipulator which is pivoted in the casing 5 by rivet 9; 10—10 are strong springs located at each side of casing 5 and supply a strong resistance when the door is opened; 11—11 are ends of springs 10—10 70 engaging ears 7—7; 12—12 are eyes of screw-eyes 4—4 which engage the other ends of springs 10—10; 13 is the latch-bolt which the door engages when it is opened, and has side extensions 14—14 on either side which 75 are engaged by the recesses 23—23 in the manipulator 8, and carries a spindle 15 upon which is assembled a spring of light resistance 17; the free end of spindle 15 passes through the back lug 24 of the casing 5, and is then riveted or spread as shown by 16; 80 dotted line 18 locates the back of the casing 5; 19 is the striking-plate which is oblong to permit its use upon more than one thickness of door; 20 is the screw hole in plate 19; 21 the edge of door to which plate 19 is attached by screw 22; 25—25 are the bottom edges of 85 casing 5 turned inwardly forming a bottom on which latch-bolt 13 rests; 10' shows a spring within the casing 5 passing through opening 95 in latch-bolt 13 and engaging lug 26 of base-plate and hole 27 in casing, thereby substituting the two outside springs 10—10; 10"—10" shows another type of spring for 100 manipulating casing 5 one end resting on the base-plate 1, then engaging rivets 6—6 and extending to and engaging casing 5' which

is another shape for casing 5 Figure 5; the line $\alpha-\alpha$ indicates where the casing 5 has been cut away as shown in Figure 6.

In operation, I secure the base-plate to the door casing with screw-eyes as in Figure 1, or screws as in Figure 5 as the case may be; I then recess the edge of the door to receive the striking-plate 19 in line with latch-bolt 13.

When the door is opened the plate engages latch-bolt 13 and pushes the door check away from the door casing, pivoting the casing 5 at 6, exercising the strong spring 10 or 10'. When the door closes, the door check having returned to its former position, at rest, the striking-plate engages the latch-bolt manipulator 8 which rocks inwardly forcing the latch-bolt back within casing 5, and exercising spring 17 of light resistance.

The construction of my door check is such that the opening of the door does not cause the latch-bolt to change its position within the casing 5.

In the drawing the casing 5 is shown struck from sheet metal, but as this casing may be of various designs, one of which is shown in Figure 8, and still not depart from the scope of my invention, I do not claim a definite pattern for the same. My invention depends more upon the relative position of

the several parts, than the detailed construction of those parts; and the relative strength of the springs.

Having thus described my invention, what I claim as new and desire to protect by Letters Patent, is:—

1. A door check comprising a base-plate, a casing member pivoted thereon, a strong spring secured to the base-plate and casing member for closing said casing, a latch-bolt with a light spring within said casing, and a striking plate.

2. A door check comprising a base-plate; a casing member pivoted upon said base-plate, and having a strong spring engaging said casing and base-plate; a latch-bolt within said casing member retaining it in extended position by a spring of light resistance.

3. A door check comprising a base-plate; a casing member pivoted upon said base-plate, and having a strong spring for closing it upon the base-plate; a latch-bolt within said casing member retaining it in extended position by a spring of light resistance, and a bolt manipulator to assist in the easy action of the latch-bolt.

In testimony whereof I have affixed my signature.

HARRY E. GIFFORD.
